UNITED STATES PATENT OFFICE.

FRANK C. ROSZMAN, OF CECIL, OHIO.

SEPARATOR FOR THRESHING-MACHINES.

1,120,978.

Specification of Letters Patent.

Patented Dec. 15, 1914.

Application filed April 1, 1914. Serial No. 828,871.

To all whom it may concern:

Be it known that I, FRANK C. ROSZMAN, a citizen of the United States, residing at Cecil, in the county of Paulding and State of Ohio, have invented certain new and useful Improvements in Separators for Threshing-Machines, of which the following is a specification, reference being had to the accompanying drawings.

10. This invention relates to separators for threshing machines.

The object of the invention is to provide an article of this character which may be operated for hauling clover seed, separating pods from straw, and freeing grain and buckwheat from straw and weeds and discharging the latter from the separator, the parts being so constructed and arranged as, while insuring the saving of all the grain, 20 the discharge of the stubble and waste will be effected, and without danger of choking the machine.

With the above and other objects in view, as will appear as the nature of the invention is better understood, the same consists in the novel construction and combination of parts of the separator, as will be herein-after described and claimed.

In the accompanying drawings forming a 30 part of this specification, and in which like characters of reference designate corresponding parts: Figure 1 is a view in perspective of one form of the separator; Fig. 2 is a transverse sectional view on an enlarged scale through the separator shown in Fig. 1; Fig. 3 is a detail view of one of the elements employed in connection with the separator; Fig. 4 is a perspective detail view of a portion of a modified form of the 40 separator; Fig. 5 is a transverse sectional view, on an enlarged scale, through the separator shown in Fig. 4.

In the form of the invention shown in Fig. 1 the separator comprises three spaced frame bars 1, 2 and 3, the upper surfaces of which are provided with angular steps 4. These bars may be made of any suitable material, and are connected and rendered rigid by end bars 5. Secured to the side bars 1 and 2 and extending any desired distance above the apices of the steps are guards 6, the forward end of the separator being provided with a similar guard 7 adjacent to which is arranged a platform 8 on which 50 the material is discharged.

Secured to the steps of the frame bars are the slats 9, which, usually, are constructed of metal, and have their inner end walls disposed at an inward angle to the top of the step to provide back walls 10 which serve 60 to direct the separated grain into a suitable receptacle. The front and rear edge portions of each pair of slats are connected by stay bolts 11 carrying nuts 12, one turned against the upper side of one slat and the 65 other against the under side of the other, and upon certain of the stay bolts is disposed a sleeve 13 having extensions 14, the object of the stay bolts and sleeves being to prevent distortion of the slats in either direction. 70

It will be seen from the foregoing description that this form of separator will be thoroughly effective in separating the grain from the material containing it, and that ample space is provided to permit escape of 75 stubble and the like between the superposed slats without any danger of choking, the stay bolts serving to prevent any grain from escaping lengthwise, so that thorough hulling will be secured. 80

In the form of the invention shown in Figs. 4 and 5 the construction of the frame is the same, the difference residing in the arrangement of slats. The front ends of the slats are provided with teeth 15, and to the 85 rear inclined portion of the slats, on their under side, are secured V-shaped back walls 16 which are secured to the slats by a rivet 17. This form of separator will be found adapted for accomplishing the separation 90 of finer grades of seeds, but in both cases the result aimed at is secured in a thoroughly practical manner.

Having thus described my invention what I claim is:

In a separator for threshing machines, a 95 frame comprising stepped bars, slats secured to the frame bars and having obliquely disposed deflecting walls projecting below the upper surface of the slats, removable bolts connecting the longitudinal edges of the slats, and winged sleeves arranged upon certain of the bolts to prevent distortion of the slats. 100

In testimony whereof I hereunto affix my 105 signature in the presence of two witnesses.

FRANK C. ROSZMAN.

Witnesses:

EDW. McGAHANAN,
JOE CAVANAGH.
